UNITED STATES PATENT OFFICE.

L. G. KNIFFEN, OF WORCESTER, MASSACHUSETTS.

IMPROVEMENT IN MOWING-MACHINES.

Specification forming part of Letters Patent No. 33,998, dated December 24, 1861.

To all whom it may concern:

Be it known that I, L. G. KNIFFEN, of Worcester, in the county of Worcester and State of Massachusetts, have invented certain new and useful Improvements in Mowing-Machines; and I do hereby declare that the following is a full, clear, and exact description of the same, reference being had to the annexed drawings, forming a part of this specification, in which—

Figure 1 represents a perspective view of the machine as it appears when the finger-beam rests on the ground and the tongue is raised. Fig. 2 represents a front view of the machine, the tongue being raised and the finger-beam, cutter-bar, and cutters being shown in three different positions.

In the drawings, A represents the main frame, composed of longitudinal and cross pieces properly fastened together, as fully indicated in the drawings. This frame A is suspended from the axle B of the wheels C C by means of boxes or bearings a a, to be fastened in any well-known manner to the main frame.

D is the tongue or draft-beam, to which the team is to be fastened or hitched in any of the well-known methods. The rear of tongue D is fastened in a groove or recess in the projection b of the metal piece E. The axle B is run or passed through a hole in the rear of piece E, whereby the connection of the tongue is formed with the machine without the use of cap-pieces and screws. As it is sometimes desirable to set or adjust the tongue D to the right or left, the rear of piece E is slotted out near its center, and a collar or adjusting-ring, c, is slipped onto the axle B as it is passed through the piece E, so as to occupy a place on said axle, as indicated in dotted lines, Fig. 1. The collar or adjusting-ring c is provided with a bolt or set-screw, d, whereby it can be fastened to axle B, so as to hold the piece E and tongue D in any desired position, either to the right or left on axle B. By this mode of construction the line of draft can be very quickly changed to suit the circumstances of the case.

F is the driver's seat, supported by the metal arm G, fastened to the rear of tongue D and the front projection of the piece E by bolts or screws which pass through all three pieces, and thus render separate bolts or screws for fastening the tongue D and piece E to-

gether unnecessary. To the under side of the front inner corner is fastened the coupling metal piece H, provided with two sets of arms, e e, which project out and down, and between which the ears f of the shoe I are hinged, as indicated in the drawings.

Shoe I supports the heel of the finger-beam J, to which are fastened the guards g g, over which the cutters i i, fastened to the cutter-bar h, work. The outer end of the finger-beam is provided with a hollow shoe, K, having a slot on its outside, whereby a small wheel can be used to support the outer end of the finger-beam. Shoe K is open on the inner side, so that the wheel is passed in from that side, the end of its journal passing through the slot in the outside of K, and by means of a nut applied thereto said wheel can be set to hold the outer end of the finger-beam at different heights from the ground, or let it rest entirely on the ground.

To the rear of shoe K are fastened the curved track-board L and curved arm M, both rigidly. By the conjoint action of L and M the cut grass is separated from that which is left standing and thrown inward from the latter toward the machine, whereby a clear path for shoe I on the next round is secured. Shoe K is provided with an opening or slot, l, so that the outer end of the cutter-bar h and outer cutter can work through the same, the cutter-bar being retained in position by guide-pieces j, fastened to the top of the finger-beam. (See Fig. 1.)

As it is desirable that the driver should be able to control the finger-beam or raise the same from the ground, a bent bearing or hanger piece, O, is fastened to tongue D, so as to project on its inner side, where it supports a guide-pulley, m, as indicated in Fig. 1, and over which passes chain n, which is fastened in front to the lip o of the metal piece H, and in rear to lever P, hinged to the frame A at p. Supposing the front of the tongue to be supported by the team, it will be observed that if the driver takes hold of lever P and draws it back, the front of the frame will be raised, and consequently shoe I with it, together with the entire finger-beam, until the parts assume position 1, Fig. 2, when, if lever P is still further depressed, so as to be caught under catch Q, fastened to the rear of the frame, the finger-beam and cutter will be made to assume

position 2, Fig. 2. In this position the machine can be moved without throwing the gearing out of action, while the elevation of the finger-beam is such as to enable the machine to pass over or by quite large stumps or stones. When, however, it is desired to fold the finger-beam still nearer the machine, the gearing is thrown out of action, and the driver, taking hold of the outer end of the finger-beam, or its parts L M, draws the finger-beam into an upright position at the side of the machine, as indicated in position 3, Fig. 2, the curved piece L just clearing the inner wheel. When in this position, the finger-beam is kept in place by a catch or latch piece, s, hinged to the top of the frame A, and projecting out so that its notch t will catch on the back of the finger-beam. Catch-piece s is forced forward by the front end of a curved spring, u, fastened to the second cross-piece of the main frame. Latch s is therefore self-operating so far as the folding of the finger-beam up is concerned, but has to be withdrawn before the finger-beam can be unfolded, and for which purpose a small foot-lever or device could be attached, so as to obviate the necessity of the driver using his hand for that purpose. The reason why the entire finger-beam is raised in nearly a horizontal position, as seen at 1, Fig. 2, by simply raising the front of the frame is the fact there is a short knuckle, v, Fig. 2, on the side of shoe I, and which strikes against the foot w of piece q, which is hinged between the rear arms, e e, of piece H, as fully indicated in the drawings. To the top of piece q is hinged or pivoted the upright arm x, which passes up through a hole in the side piece of frame A, and is provided on its top with a head or cap, y, so that when lever P is depressed lower than is sufficient to raise the finger-beam into position 1, Fig. 2, it comes in contact with cap or head y on arm x, and forces the latter down, thus causing foot w to press down knuckle v, whereby the outer end of the finger-beam is caused to rise, as indicated in position 2, Fig. 2. The form of piece q is shown in Fig. 3. To unfold the finger-beam, the driver withdraws the latch s, and then pulls lever P out from under catch Q, and lets the lever up gradually after having turned the finger-beam down by hand into position 2, Fig. 2, until the finger-beam rests upon the ground, as indicated in Fig. 1.

The driver's seat is projected back in rear of axle B, whereby there is a tendency to tip up the tongue; but the front of frame A is suspended from tongue D by means of chain z, fastened at its lower end to frame A and hitched in a slit in the rigid arm R, fastened to the rear of tongue D. The height of shoe I from the ground can be controlled by adjusting chain z. The slit in the end of R, being just wide enough to receive the link when presented edgewise, prevents the chain from drawing down.

There are quite a number of advantages attending the use of chain z and arm R for sup-

porting the front of the frame, so as to cause shoe I to press with any desired pressure on the stubble and ground, some of which may be mentioned. It enables the frame to be suspended at a point nearly or quite over the center of the crank-shaft S, which operates the pitman T to give the requisite reciprocating motion to the cutter-bar and its cutters, whereby much of the jarring is prevented which is found to exist in machines in which such suspension is from the opposite side of the frame from the crank-shaft. Again, the machine is more quickly adjusted and with less danger than in the modes heretofore adopted and applied on the opposite side of the machine.

The upper end of the chain Z is to be properly hooked or fastened to arm R, so that it cannot drop down onto the ground. One advantage gained by attaching the lower curved track-piece, L, rigidly to the shoe K is that when so connected its rear end, by being depressed when the finger-beam is raised, strikes against the ground, and thus serves to elevate the outer end of the finger-beam and keep it up even with the heel end. (See Fig. 2.) In consequence of this function of the part L there can be left greater play between the knuckle v and foot w when the machine is in operation, whereby either end of the finger-beam can rise and fall, or the entire bar, to conform to the irregularities of the ground with greater freedom than otherwise.

Pitman T is connected to the head of the crank-pin, which projects from the balance-wheel on the front end of the crank-shaft S. The mode of constructing the joint is not new; but the arrangement of the joint in the place and manner shown enables it to perform an additional function from what it does in ordinary use. As here used, the front of the socket is all smooth, and answers the purpose of a shield to prevent cut stalks of grass from falling against and winding up on the end of the crank-pin. The team can be hitched up closer, too, without danger of the crank being clogged by catching stalks thrown up by their feet.

Motion is imparted to shaft S from the main wheel in this instance by means of a bevel-gear, U, fast on axle B, acting upon a small bevel-gear, V, on the rear of shaft S, the latter being sustained in suitable bearings on frame A, and connected to the cutter-bar by means of pitman T. Any of the common and well-known methods of throwing the cutter out of action may be applied to this machine. W is a staple fastened to support the pitman and cutter-bar when the latter is folded, as seen in Fig. 2.

The main wheels C C are fastened to axle B; but they might be connected by pawls and ratchets, so as not to operate the cutters when the machine is backed.

Having thus described my improved machine, what I claim as my invention, and desire to secure by Letters Patent, is—

1. The combination, with the front inner

corner of the main frame and rear inner side of tongue D, of shoe I, coupling or connecting piece H, bent bearing-piece O, with its pulley m, chain n, and lever P, substantially as and for the purposes set forth.

2. The combination of piece q and pivoted arm x with shoe I and lever P, substantially as and for the purposes set forth.

3. The combination of the rigid track-piece L with a finger-beam hinged to the front inner corner of a main frame having a hinged tongue, and the elevating-lever, as and for the purposes set forth.

4. Suspending the front of the frame from the tongue by means of chain z and arm R, substantially as described.

5. The combination of the metal piece E and collar e with axle B and tongue D, as described.

In witness whereof I have hereunto subscribed my name.

L. G. KNIFFEN.

In presence of—

THOS. H. DODGE,
ALBYRUS BROWN.
